UNITED STATES PATENT OFFICE.

THOMAS DAVIS, OF OKMULGEE COUNTY, OKLAHOMA.

TIGHTENING DEVICE.

1,366,904.

Specification of Letters Patent.

Patented Feb. 1, 1921.

Application filed July 20, 1918. Serial No. 245,887.

To all whom it may concern:

Be it known that I, THOMAS DAVIS, a citizen of the United States, residing in Okmulgee county and State of Oklahoma, have 5 invented certain new and useful Improvements in Tightening Devices, of which the following is a specification, reference being had to the accompanying drawings.

This invention relates to an improved 10 tightening device for the belts of radiator fans such as are commonly used in connection with vehicle motors, and has for its primary object to provide a device primarily designed for use in connection with a well 15 known type of vehicle motor, whereby the fan belt may be properly adjusted and maintained at the desired tension.

It is another object of the invention to provide a device applicable to the vehicle 20 motor without necessitating any alterations whatever in the fan shaft mounting.

It is a more particular object of the invention to provide a device for the above 25 purpose consisting of a resilient element adapted to be secured at one of its ends by the adjusting bolt for the fan shaft bracket, and an adjustable connection between the 30 other end of said element and the shaft bracket, whereby the bracket may be properly adjusted to tighten the belt.

And it is a further general object of my 35 invention to provide a device for the above purpose which is exceedingly simple as well as durable in its construction, highly servicable and convenient for the purpose in view, and which can be manufactured and sold at relatively small cost.

With the above and other objects in view, 40 the invention consists in the improved construction, combination and arrangement of the several parts as will be hereinafter more fully described, subsequently claimed and illustrated in the accompanying drawing in which similar reference characters designate 45 corresponding parts throughout the several views, and wherein:—

Figure 1 is a rear end elevation of the fan 50 shaft mounting illustrating the preferred embodiment of my improved tightening device in its applied position;

Fig. 2 is a plan view; and

Figs. 3 and 4 are perspective views of the parts of the device disassembled.

Referring in detail to the drawing, where- 55 in I have illustrated the mounting and arrangement of the radiator fan as found in

the Ford motor vehicle construction, 5 designates the fan shaft bracket which is mounted at one of its ends for swinging or pivotal movement upon the bolt 6. This 60 end of the bracket is formed with a toe or extension 7 which is engaged by a set screw 8 threaded in a lug 9 on the casing which houses the cam shaft gears of the motor. In the other end of the bracket 5, the fan 65 shaft 10 is journaled, and has the fan 11 fixed to its forward end. Between the bracket and the fan, the belt wheel 12 is fixed on the shaft 10 around which the belt 13 is engaged which extends from a similar 70 wheel fixed upon the motor shaft. It will be understood that all of the parts just described constitute the fan shaft mounting as now in general use and comprise no part 75 of my invention. The adjusting screw 8 permits of a very limited range of adjustment of the fan shaft bracket. By means of my invention which I shall now proceed to describe in detail, the tension upon the fan belt may be more precisely regulated in 80 accordance with the strength of the belt, and the objection to the adjustable set screw above noted obviated.

With the above end in view, I provide a rod of resilient spring metal having a single 85 coil 14 formed therein. One end 15 of this coil is extended in radial relation thereto and terminates in an eye 16, which is adapted to receive the set screw or bolt 8 above referred to and to be secured between the 90 head of said bolt and the lug 9. The other end 17 of the rod 14 projects in an opposite direction tangentially from the coil 15 and also terminates in an eye 18. The threaded end of a rod 19 is engaged through 95 this latter eye. Upon the other end of said rod, a hook 20 is formed. This hook is adapted for engagement around the far side of the bracket 5 at the rear thereof. An adjusting nut 21 is threaded upon the end of 100 the rod 19 and by engagement with the eye 18 draws the rod through said eye to swing the bracket and angularly position the same with relation to the axis of the supporting bolt 6. A lock nut 22 for the nut 21 is also 105 threaded upon the end of the rod 19. It will thus be apparent that by adjusting the nut 21 to swing the bracket upwardly, the fan shaft will be raised and the belt tightened upon the wheel 12. If the belt is of 110 weak construction, the adjustment should not be made too tight, as the belt would be

liable to break. If a belt of chain or other metal construction is employed, this probability does not exist and the adjustment may be made very solid and strong. By providing the resilient tension applying element 14, the tension may be regulated to a nicety, and violent shocks or jars to which the motor may be subjected will be absorbed by this tensioning element, whereby the possible breakage of the bracket or the fan shaft is obviated.

From the foregoing description, taken in connection with the accompanying drawing, the construction, manner of application and use, and several advantages of the invention will be clearly and fully understood. It will be seen that the device can be readily applied in its operative position without necessitating any alterations whatever in the fan mounting with which the motor is equipped. The several parts of the device are of very simple form so that the tensioning device will be strong and durable, as well as serviceable and efficient in practical use, and likewise capable of manufacture at comparatively small cost.

While I have herein shown and described the preferred form and construction of the various elements, it is to be understood that the device is susceptible of considerable modification therein and I, accordingly, reserve the privilege of adopting all such legitimate changes as may be fairly embodied within the spirit and scope of the invention as claimed.

I claim:—

In a tightening device, a support having an upstanding bearing, a fan shaft bracket having a bearing for a fan shaft and pro-

vided with a radial lug alined with the bracket, means passing through the bracket adjacent where the lug unites therewith and pivotally mounting the bracket on said bearing, an adjusting screw mounted on and carried by the support and adapted to coöperate with the lug to limit the bracket in its movement in one direction, a single coil spring disposed in a plane with the bearing and being detachably carried on the screw, said single coil having a relatively rigid arm, a screw carried by the terminal of the rigid arm, nuts on opposite sides of the rigid arm terminal and being adjustably threaded to the second screw for holding the second screw adjusted and in a position at right angles to the arm, one end of the second screw terminating in a hook engaging the fan shaft bracket, said rigid arm being offset to the side and in a plane slightly in advance of the bracket and having its terminal disposed at a point below the fan shaft, whereby should the belt break, the bracket will wipe frictionally against the second screw and then contact with one of the nuts and limit the bracket in its movement and at the same time cushion the bracket and rebound it in contact with the hook, said second screw adapted to be adjusted to increase or decrease the tension of the coil and thereby increasing or decreasing the tightness of the belt.

In testimony whereof I hereunto affix my signature in the presence of two witnesses.

THOMAS DAVIS.
